GRAINING OF LITHOGRAPHIC AND OTHER PRINTING PLATES

Johan Gunnar Lindmark, Stockholm, Sweden,
assignor to Aktiebolaget Johnson & Borsell,
Stockholm, Sweden, a corporation of Sweden

Application April 13, 1949, Serial No. 87,313
In Sweden January 26, 1945

4 Claims. (Cl. 51—282)

1

This application is a continuation-in-part of my copending application, Serial No. 643,271, filed January 25, 1946, now Patent No. 2,495,269. This prior application is directed to an apparatus which can be used for conducting the process which is described and claimed in the present application.

In the lithographic and offset printing process it is highly important for obtaining sharp and accurate printed impressions to provide printing plates the porous surfaces of which will absorb uniformly a maximum quantity of character forming media, such as, lithographic ink, for the design and also a maximum of moisture on the portion not covered by the design. In order to obtain this maximum absorptivity it is well recognized that the pores in the surface of the plate should be as deep as possible and of uniform depth and size. In the past it has not been possible to produce lithographic plates whose porous surfaces are free from waves, craters and other imperfections which cause a non-uniform and insufficient absorption of ink or water. Accurate reproduction of grained surfaces was likewise impossible.

Various methods of graining plates have been used heretofore but none of them have been entirely satisfactory.

In the most frequently used method a so-called shaking or graining box is used, this box being furnished with water, steel balls and a graining material. The plates to be grained are mounted in the box and the box is then shaken to produce the grinding effect. Imperfections are frequently present in the plates produced by this method and the depth of the grain is not wholly satisfactory. Moreover the grain produced by this method in any given operation cannot be reproduced since the steel balls wear down rather rapidly and the graining depends upon the size and weight of these balls. Moreover a considerable amount of corrosion and oxidation occurs in these graining boxes due to the presence of water and air. The method is both slow and dirty.

While various proposals have been made to employ sand blasting equipment to grain lithographic plates, none of these have been found sufficiently satisfactory to have been adopted to any important extent. Many of these machines use a blast of sand and water and in these machines corrosion occurs. In some of these blasting machines the work has been mounted flat and this has invariably caused the formation of waves in the work. In others the work has been mounted on drums which rotate slowly

2

in front of the blasts. It has been found impossible in these machines to produce grains of uniform size and depth. Numerous pits and craters are always present.

5 It is an object of the present invention to provide a method having a rate of production substantially double that of the conventional graining boxes.

Another object is to provide a method which 10 is clean, in which no oxidation occurs, which requires no preliminary lye treatment or cleaning of the plates to be grained and which produces plates which can be used immediately or stored indefinitely without deterioration.

15 A further object is to provide a method in which the sand or other grit consumed is a small fraction of that consumed by other processes.

It is still another object of this invention to 20 produce grained printing plates having an extremely uniform texture of grain substantially free from pits and craters which texture can be reproduced accurately at any future time merely by the use of the same operating conditions.

I have found that the above and other objects 25 can be accomplished and the enumerated difficulties overcome by my novel process which consists in mounting the work to be grained on a drum or other rotatable support, rotating said support at a high critical peripheral speed while 30 directing a high velocity blast of grinding material against said work and moving said blast longitudinally back and forth at a relatively slow speed during the graining operation.

In the tests which led up to the present invention I made a discovery which I believe accounts for the failure of prior sand blasting methods to produce grains of uniform texture free from pits and craters. I found that if the plates to be grained are mounted on a drum and this drum is rotated at high speed during blasting the pits and craters substantially disappear from the grained surface. The minimum peripheral speed required to thus eliminate pits and craters is critical and in the neighborhood of 45 25 inches per second. The cause for this phenomenon is believed to be that at the high peripheral speeds in question the spent particles of sand are removed by centrifugal force from the blast area substantially immediately after they strike the plate. Sand particles which at slower speeds would tend to stick to the plate are thrown off by centrifugal force and particles which rebound from the plate regain a substantial velocity in a tangential direction due to the impelling action of the rapidly moving plate. The

chances of the high-velocity blast particles striking spent grains and driving them into the plate are substantially reduced and I believe that in prior processes pits and craters are largely produced by this action—at least that seems to be a reasonable explanation of the facts stated.

I have also found that the sand blast nozzles should be moved rather slowly in front of the rapidly moving drum in order to produce satisfactory graining for lithographic work. The best speed for this type of work I have found to be from about 5 to 25 inches per minute. Of course since my method can be applied to the graining of materials for other purposes than lithography the speeds mentioned can be varied outside the range stated. The texture of the graining produced depends upon the speed of the drum, the speed of the blast nozzles, the angle at which the blast is directed, the air pressure and the type and size of grit used. Since each of these factors can be duplicated it is possible with my method to accurately reproduce a given grain texture at any future time. It is only necessary to make a record of these factors and reproduce them later in order to accomplish this.

My process can best be explained by reference to the accompanying drawing which shows more or less diagrammatically an apparatus suitable for conducting my process. This apparatus is described more fully in my acknowledged copending application. In this showing,

Fig. 1 is a vertical longitudinal section through a blasting machine suitable for applying my process.

Fig. 2 is a sectional view, partly in elevation, taken along the line II—II in Fig. 3.

Fig. 3 is a vertical transverse section of the machine taken along the line III—III of Fig. 1.

Fig. 4 is a partial sectional view of a modification, similar to the lower portion of Fig. 2 but showing the use of a pair of blast nozzles.

Fig. 5 is a partial vertical transverse section on a larger scale, similar to the upper portion of Fig. 3, but showing a modification in which sealing means are provided for closing the slot through which the blast nozzles pass, while

Fig. 6 is a fragmental sectional view of the modification of Fig. 5, taken along the line 6—6 of this figure.

Referring to the drawings in which like parts are designated by like reference numerals, there is provided in the upper part of a closed housing 10 a drum 11, on which a lithographic printing plate 12 of zinc or other material may be secured by means of clamping jaws 13, said drum being rotatably journaled by means of a suitable shaft 14, which is driven at a variable speed from an electromotor 15 through the intermediary of a worm-wheel gearing 16. In one longitudinal wall of the housing right opposite the drum 11 there is provided a comparatively narrow rectangular opening, which is closed by means of a cylinder or guide 17 journaled in the housing so as to be rotatable around its own axis. Diametrically extending through said cylinder a slot 18 is provided through which a reciprocable sand blast nozzle 19 projects into the housing. The reciprocating movement of the blast nozzle 19 is derived from a longitudinally extending screw spindle 20, which is journaled in end plates 21 united with the cylinder 17 and cooperates with a nut 22 which is connected with a holder 23 in which the nozzle 19 is axially displaceable for the purpose of setting the nozzle at the desired distance from the drum. The screw spindle 20 is

driven by means of a worm-wheel gearing or belt drive 25 at a variable speed from an electric motor 24 mounted on the projecting end of the shaft of the cylinder 17. For reversing the direction of rotation of the motor 24 and of the screw spindle 20 at the turning points of the nozzle there are provided adjustable limit abutments 26 which change the direction of the rotation of the motor under control of the nozzle by mechanical or electrical means.

It should be clear that by turning the cylinder 17 and the parts connected therewith about the axis of the cylinder the angle between the envelope surface of the drum 11 and the blast nozzle 19 may be adjusted to every suitable value. For locking the cylinder in the adjusted position there is provided a locking device 27.

The interior of the housing 10 is in communication with a suction fan or the like through an intermediary of a conduit 28 so that a subatmospheric pressure is always maintained in the machine, whereby dust is prevented from emerging into the workroom. To reduce the air consumption the guide slot 18 for the blast nozzle 19 may be closed, if desired, by means of an elastic sealing device, for instance consisting of two flexible bands of rubber or the like, as shown at 29 and 30 in Figs. 5 and 6 which bands in their normal position cover the slit opening.

During the sand blasting operation the drum 11 is preferably rotated at such a high speed that the stresses in the printing plate 12 clamped to the drum are increased considerably through the action of the centrifugal force. The drum used may vary in size from about 40 to 70 centimeters in diameter with a preferred diameter of from about 50 to 60 centimeters.

To avoid patterning, the velocity of movement of the nozzle should be so selected with respect to the speed of rotation of the drum that the nozzle is not periodically directed to exactly the same points of the printing plate. As mentioned previously the best nozzle speed for the graining of lithographic plates is from about 5 to 25 inches per minute.

The distance of the nozzle from the work is also important and best results are obtained when this distance is within the range of about 2 to 6 inches with a preferred range of about 3 to 4 inches. If two or more nozzles are employed the blasts should diverge at such an angle that there is no overlapping of the blasts where they meet the work. The air pressure which operates the blast must be kept highly constant. Best results are obtained when the pressure at the blast is within the range of about 15 to 70 pounds per square inch while the preferred pressure range is from about 25 to 50 pounds per square inch.

The angle of incidence of the blast with the work determines the depth as well as the shape of the grains. This angle can be varied from about 90° to 45° in both directions but, of course, the texture of the grain will differ considerably as the angle is varied within this range. The type of impression desired will largely determine the best angle of incidence to be employed.

I have found that the grain of plates grained by my process has an average depth at least 50% greater than plates grained by other processes. A uniformity is obtained which is not possible by other methods. When a single blast nozzle is used plates can be grained in from 7 to 14 minutes depending on their size while with more than one nozzle this time can be reduced still

further. These plates are capable of absorbing uniformly a far greater amount of water and ink.

I have found that plates made by my process are entirely free from waves, craters and pits and other imperfections ordinarily present in grained plates produced by other processes. I have also found that the use of my process will not result in oxidation either of the plates or of the metal grinding particles when metal is used as the grinding medium.

It is a further important feature of my invention that the sub-atmospheric pressure under which the process is conducted keeps the operating area as well as the surface of the plates free from dust.

While I have described what I believe to be the most advantageous embodiments of my invention it is evident of course that various modifications can be made in the specific procedures described without departing from the purview of my invention. My process is applicable for the graining of plates made of various materials such as plastic or metals such as stainless steel, copper, aluminum and zinc. Although I prefer to use ordinary sea sand as the blasting material other types of sand are suitable as well as "carborundum," saw dust, powdered glass, metal powders, "alundum" and emery. I preferably use air as the propelling means for the sand or other grinding material but other gases may be used if desired such as nitrogen, steam, carbon dioxide or other non-oxidizing gases.

The machine used in my process may be provided with means for moistening the plate to be grained with water or other liquid during the sand blasting operation as shown in 31 in Fig. 5. It is also possible to employ a plurality of blast nozzles 10', as shown in Fig. 4 of the drawing. It should also be clear that as concerns the use of my novel process for treating the surface of old lithographic printing plates, the process can be used not only for graining the surface of a printing plate from which the old lithographic picture has been removed as by washing with a suitable solvent, but also for the removal of the old impression prior to graining. Other modifications of my invention which fall within the scope of the following claims will be immediately evident to those skilled in the art.

I claim:

1. In the process of graining lithographic and other printing plates as well as plastic sheets used in the art of offset printing, the process which comprises mounting the work to be grained on a rotatable drum, rotating said drum at a peripheral speed of at least about 25 inches per second,

directing a high-velocity blast of grinding material against the work at an angle of incidence within the range of from 45° to 90° and under a nozzle pressure of from about 15 to 70 pounds per square inch, and moving said blast longitudinally at a slow constant speed along said drum.

2. In the process of graining lithographic and other printing plates as well as plastic sheets used in the art of offset printing, the process which

10 comprises mounting the work to be grained on a rotatable drum, rotating said drum at a peripheral speed of from about 25 to 150 inches per second, directing a high-velocity blast of grinding material against the work, reciprocating said

15 blast longitudinally at a slow constant speed along said drum and maintaining a subatmospheric pressure in the neighborhood of the blast.

3. In the process of graining lithographic and other printing plates as well as plastic sheets used in the art of offset printing, the process which

20 comprises mounting the work to be grained on a rotatable drum, rotating said drum at a peripheral speed of from about 25 to 150 inches per second, directing a high-velocity blast of grinding

25 material against the work under a nozzle pressure of from about 15 to 70 pounds per square inch, moving said blast longitudinally at a constant speed of about 5 to 25 inches per minute along said drum and maintaining a subatmospheric pressure in the neighborhood of the blast.

30 4. In the process of graining lithographic and other printing plates as well as plastic sheets used in the art of offset printing, the process which

35 comprises mounting the work to be grained on a rotatable drum, rotating said drum at a peripheral speed of about 65 inches per second, directing a high-velocity blast of grinding material against the work under a nozzle pressure of about 40 pounds per square inch, moving said blast longitudinally at a constant speed of about 10 inches per minute back and forth along said drum and maintaining a subatmospheric pressure in the neighborhood of the blast.
